UNITED STATES PATENT OFFICE.

JERRY J. LYNCH, OF ERIE, PENNSYLVANIA.

DESIGN FOR A TROUSERS-STRETCHER.

SPECIFICATION forming part of Design No. 28,647, dated May 17, 1898.

Application filed April 9, 1898. Serial No. 677,094. Term of patent 7 years.

To all whom it may concern:

Be it known that I, JERRY J. LYNCH, a citizen of the United States, residing at Erie, in the county of Erie and State of Pennsylvania, have invented a certain new and useful Design for Trousers-Stretchers; and I do declare the following to be a full, clear, and exact description of the invention, such as will enable others skilled in the art to which it appertains to make and use the same, reference being had to the accompanying drawing, and to the letters of reference marked thereon, which forms a part of this specification.

This invention relates to a certain new and useful design for trousers-stretchers such as are used to stretch and hold the trousers from wrinkling and retain the longitudinal creases in the legs of the trousers.

My design is clearly illustrated in the accompanying drawing, in which I have shown a perspective view of the stretcher.

The design consists of the body portion, which is solid, the ends being forked, the arms of the forked portions being twisted at A, so as to be disposed at right angles to the body portion of the stretcher. The inner margins of the forks are curved, slightly tapering toward their extreme ends, and are provided with a series of inwardly or rearwardly extending teeth, as shown. 30

What I claim to be new, and desire to secure by Letters Patent, is—

The design for a trousers-stretcher substantially as hereinbefore described and illustrated in the accompanying drawing. 35

In testimony whereof I affix my signature in presence of two witnesses.

JERRY J. LYNCH.
